UNITED STATES PATENT OFFICE.

JAMES T. DICKSON, OF LOS ANGELES, CALIFORNIA.

VACUUM-BRAKE.

1,076,198.

Specification of Letters Patent. Patented Oct. 21, 1913.

Application filed August 7, 1912. Serial No. 713,896.

To all whom it may concern:

Be it known that I, JAMES T. DICKSON, a citizen of the United States, residing at Los Angeles, in the county of Los Angeles, State of California, have invented new and useful Improvements in Vacuum-Brakes, of which the following is a specification.

The prime object of my invention is to provide a brake actuated by vacuum, adapted for automobiles and like uses; and it comprises a mechanism operatively connected to the intake manifold of an internal combustion engine, at any suitable point between the carburetor throttle valve and cylinders, so that the suction created by the engine when the throttle is closed may be employed for braking purposes.

My invention in its most approved form is set forth in the following specification, taken in connection with the accompanying drawings, in which;

Figure 1 is a general elevation showing the application of my device to an automobile. Fig. 2 is a detail section of a three way suction controlling valve. Fig. 3 is a detail showing a method of operating the brake band.

In the drawings 5 designates the engine of any typical automobile, 6 the intake manifold and 7 the carburetor connected thereto. On the steering post 8 I have shown a suitable lever 9 operating throttle 15 through connecting rods 10, 11 and 12, and bell cranks 13 and 14 located at a convenient point on the vehicle; a horizontally disposed cylinder 16, open at one end and having therein a piston 17, suitably packed; this piston having a link connection as at 18, which extends out a suitable distance and is provided at its outer end with a slotted way 19 for the purpose of attaching thereto the lower end of foot lever 20, the attachment being preferably by means of a cross pin 21 which permits the lever to slide back and forth to the extent of the slotted way 19, allowing the foot lever 20 to be used for braking purposes at the option of the operator and without affecting the piston.

Above the pivot point 22 of the foot lever 20 is the connecting rod 23 which extends to brake 24. Brake 24 may be operable in any common manner; I have shown an arrangement in Fig. 3 whereby the movement of rod 23 in the direction indicated will close the brake band 24^a on the drum 24^b.

The manifold 6 is connected with the head

of the cylinder 16 by means of a pipe 25, and in the line of the pipe at any suitable point is a three way valve 26, the stem of the valve having arms 27 and 28. To the arm 28 is hinged a manually operable rod 29, whereby the operator may be able to open or close the valve and thus control the passage of suction through the pipe. The spring 30 returns the valve to a closed position; admitting air to the cylinder 16 which in turn releases the brake. Through the rod 31 the arm 27 is connected with the throttle valve operating means at 32. The end of the rod 31 is provided with a slotted way 33 to permit the operation of the valve 26 through the operating rod 29 without affecting the movement of the throttle valve 32. Either of these valve operating means may be used to the exclusion of the other. Being thus connected up it is obvious that when it is desired to slow down the engine and the throttle is closed, either partially or wholly, there will be produced a partial vacuum in the intake pipe 6 and in pipe 25. The opening of valve 26 will cause sufficient vacuum to act on piston 17 in cylinder 16 to move the piston 17 and thereby operate the foot lever 20 and this in turn actuates the brake through the brake rod 11. The valve 26 will rotate through approximately a quarter rotation to make a clear passage through pipe 25; a position intermediate this and the one illustrated will cut off all connection of cylinder 16 through pipe 25 and will hold a vacuum in the cylinder. The pressure exerted on piston 17 will depend upon the extent to which the engine is throttled. If the engine is running at high speed and is suddenly throttled excessively, the vacuum produced is comparatively large and the braking power is similarly heavy. The vacuum is produced when the engine is throttled down; and the engine is always throttled when it is desired to stop the car. As soon as the braking action has taken place and the valve 26 cuts off the suction from the manifold the piston will still hold the brake in contact, until the stem of the valve is so turned as to cause air to fill the space behind the piston. This method of operation is easily done through the valve operating rod 29. However it will be understood that the apparatus is at least operative without valve control in the pipe 25. When the engine is running under normal conditions

with the throttle wholly or widely open, there is a very slight vacuum created in the intake; and, consequently, there would be very little pressure tending to move the piston 17. But when the engine is throttled down the vacuum pressure, due to the engine suction, increases and will move the piston to apply the brake at the same time the engine slows down. The primary function of 10 the valve 26 (when the foot operation is used) is to provide for applying the brake only when wanted, and not every time the engine feed is cut off.

Having described my invention, I claim: 15 1. In combination, an internal combustion engine having a throttle controlled intake pipe, a brake applied to a mechanism driven by the engine, a vacuum cylinder, a piston therein, and a pipe connection between the 20 manifold and cylinder.

2. In combination, an internal combustion engine having a throttle controlled intake manifold, a brake applied to a part rotated by the engine, a vacuum cylinder, a piston 25 therein and operatively connected to the brake, and a pipe connection between the manifold and cylinder provided with a manually operable three way valve for controlling the connection of the cylinder to the 30 manifold or to atmosphere.

3. In combination, an internal combustion engine having a throttle controlled intake manifold, a brake for the engine, a vacuum cylinder, a piston therein, a foot lever connected with the brake and attached to the piston with a limited sliding movement with 35 respect thereto, and suction connection between the cylinder and the intake manifold between the throttle and engine.

40 4. In combination, an internal combustion

engine, an intake manifold, a throttle valve therefor, a brake for the engine, a vacuum cylinder and a piston therein connected with the brake, a pipe connection between the cylinder and manifold at a point between the throttle and engine, a three way valve in said pipe, and mechanical connections between the engine throttle valve and the three way valve.

5. In combination, an internal combustion 50 engine having a throttle controlled intake, a brake operating upon the engine, vacuum operable means for actuating the brake, and connection between said means and the intake at a point between the engine and 55 throttle.

6. In combination, an internal combustion engine having a throttle controlled intake, a brake for the engine, vacuum operable means for actuating the brake, connection 60 between said means and the intake at a point between the engine and throttle, and manually operable means controlling passage of fluid through said connection.

7. In combination, an internal combustion 65 engine having a throttle controlled intake, a brake for the engine, vacuum operable means for actuating the brake, connection between said means and the intake at a point between the engine and throttle, a 70 valve in said connection and manually operable means whereby the throttle and valve may be simultaneously operated.

In witness that I claim the foregoing I have hereunto subscribed my name this 19th 75 day of July 1912.

JAMES T. DICKSON.

DISCLAIMER

1,076,198.—James T. Dickson, Los Angeles, Calif. VACUUM BRAKES. Patent dated October 21, 1913. Disclaimer filed June 10, 1930, by the assignee, Bragg-Kliesrath Corporation.

Hereby enters this disclaimer to that part of the claim in said specification which appears as claims numbered 1, 3 and 5, and which are in the following words, to wit:

“1. In combination, an internal combustion engine having a throttle controlled intake pipe, a brake applied to a mechanism driven by the engine, a vacuum cylinder, a piston therein, and a pipe connection between the manifold and cylinder.”

“3. In combination, an internal combustion engine having a throttle controlled intake manifold, a brake for the engine, a vacuum cylinder, a piston therein, a foot lever connected with the brake and attached to the piston with a limited sliding movement with respect thereto, and suction connection between the cylinder and the intake manifold between the throttle and engine.”

“5. In combination, an internal combustion engine having a throttle controlled intake, a brake operating upon the engine, vacuum operable means for actuating the brake, and connection between said means and the intake at a point between the engine and throttle.”

[Official Gazette July 1, 1930]

with the throttle wholly or widely open, there is a very slight vacuum created in the intake; and, consequently, there would be very little pressure tending to move the piston 17. But when the engine is throttled down the vacuum pressure, due to the engine suction, increases and will move the piston to apply the brake at the same time the engine slows down. The primary function of 10 the valve 26 (when the foot operation is used) is to provide for applying the brake only when wanted, and not every time the engine feed is cut off.

Having described my invention, I claim: 15 1. In combination, an internal combustion engine having a throttle controlled intake pipe, a brake applied to a mechanism driven by the engine, a vacuum cylinder, a piston therein, and a pipe connection between the 20 manifold and cylinder.

2. In combination, an internal combustion engine having a throttle controlled intake manifold, a brake applied to a part rotated by the engine, a vacuum cylinder, a piston 25 therein and operatively connected to the brake, and a pipe connection between the manifold and cylinder provided with a manually operable three way valve for controlling the connection of the cylinder to the 30 manifold or to atmosphere.

3. In combination, an internal combustion engine having a throttle controlled intake manifold, a brake for the engine, a vacuum cylinder, a piston therein, a foot lever connected with the brake and attached to the piston with a limited sliding movement with 35 respect thereto, and suction connection between the cylinder and the intake manifold between the throttle and engine.

40 4. In combination, an internal combustion

engine, an intake manifold, a throttle valve therefor, a brake for the engine, a vacuum cylinder and a piston therein connected with the brake, a pipe connection between the cylinder and manifold at a point between the throttle and engine, a three way valve in said pipe, and mechanical connections between the engine throttle valve and the three way valve.

5. In combination, an internal combustion 50 engine having a throttle controlled intake, a brake operating upon the engine, vacuum operable means for actuating the brake, and connection between said means and the intake at a point between the engine and 55 throttle.

6. In combination, an internal combustion engine having a throttle controlled intake, a brake for the engine, vacuum operable means for actuating the brake, connection 60 between said means and the intake at a point between the engine and throttle, and manually operable means controlling passage of fluid through said connection.

7. In combination, an internal combustion 65 engine having a throttle controlled intake, a brake for the engine, vacuum operable means for actuating the brake, connection between said means and the intake at a point between the engine and throttle, a 70 valve in said connection and manually operable means whereby the throttle and valve may be simultaneously operated.

In witness that I claim the foregoing I have hereunto subscribed my name this 19th 75 day of July 1912.
